UNITED STATES PATENT OFFICE

FRANK L. DIETZ, OF SEATTLE, WASHINGTON, ASSIGNOR TO NORTH PACIFIC CEDAR PRODUCTS CORPORATION, OF SEATTLE, WASHINGTON, A CORPORATION OF WASHINGTON

SPLIT SHAKE

Application filed April 18, 1928. Serial No. 270,955.

My invention relates to split shakes of the general type shown in Patent No. 1,577,935 to John C. Runkle, and in my Patent No. 1,663,905.

5 Hand split shakes made of high quality vertical grain western red cedar and like woods, and either split tapering as disclosed in my former patent, or resawn from ordinary hand split shakes as described in the 55 Runkle patent, have been used in increasing numbers where it is desired to add a rustic touch to a house. Such shakes may be used either on the side walls, or on the roof. However, in some instances, the owners of houses 60 10 on which such shakes have been put, complain that the shakes are too uniform, and have not the rustic appearance desired, due, primarily, to the fact that the cedar is of such quality (as it must be to make large shakes 65 15 from) that it splits too evenly and smoothly, and there is not sufficient break in the surface of the shakes. Though one is conscious of it when close to the side wall of a house covered with split shakes, this uniformity is 70 especially noticeable from a distance, where the slight corrugations and channels, due to the vagaries of the grain, are not visible, and when such a roof is viewed from below, and nearly in the plane of the roof, when the 75 20 butts are most prominent. These butts, being in the main formed with an ordinary frow, or with such a frow and a saw, appear quite as straight as the butts of ordinary sawed shingles, and lay quite as tightly. This tends 80 25 to produce an altogether uniform appearance, which is not consistent with the rusticity which such owners have expected, and desire. 85

As has been stated, the cedar, from which such shakes must be split, must be of the 90 highest quality; the grain must be perfect, for wavy-grained wood cannot be used satisfactorily for the manufacture of such shakes. It follows, then, that when such wood is split 95 40 it will split very nearly perfectly to a plane, and there will be little in the way of angled or inclined surfaces to catch the eye, or to reflect light, and to give the effect of a broken surface.

Accordingly, it is my object in the present 50 invention, to produce a shake which has a

surface which produces the appearance of being quite irregular, and which is in fact ridged, or corrugated. It is, of course, a further object to control the corrugations in such a manner that, though appearing quite irregular, they are in fact all within a common plane, at least the upper portions of the principal ridges, so that succeeding courses can be laid sufficiently tight to prevent any possibility of leakage, and without the possibility of the shakes in these succeeding courses being cocked to one side or at an angle to the general plane of the course. 55 60 65

Associated with these objects, it is a further object to provide a butt edge, at least the edge of the butt which is to be uppermost, which is waved to give the impression of irregularity when viewed from below, that is when the shake is viewed end on. 70

A further object is the provision of such a shake, which has longitudinal channels for drainage which, by virtue of being larger than those ordinarily and naturally provided, will tend better to accumulate the water in large drops and thus facilitate and assist in 75 its draining off.

A further object is the provision of a frow whereby such shakes as have been described may be split out so that the shakes can be thus produced at one operation, and require no 80 further operation upon them.

In this specification I shall employ the term "shake" to mean a board, whether tapering from butt to tip, or of substantially the same thickness throughout, and whether resawn, according to the Runkle patent, or split entirely, so long as the board has one or more faces which are naturally split from the block. My invention is applicable to shakes of all descriptions, as thus defined, and hence may apply to Runkle's resawn shakes or to the hand split tapered shakes of my former patent. 85 90

My invention comprises the novel shake, and the novel frow, for splitting the same, as shown in the accompanying drawings, described in the specification, and particularly defined by the claims terminating the same. 95

In the accompanying drawings I have 100 shown a single type of shake, and the frow

for making this or other types of shake, both in typical forms to illustrate the principle of the invention.

Figure 1, is a perspective view of a finished straight shake, ready for resawing according to the Runkle patent.

Figure 2 is a plan view of the block from which such a shake is cut, illustrating the line of cleavage of a second shake.

Figure 3 is a perspective view of the frow in splitting out such shakes.

Figure 4 is an edge view of such a frow.

Figure 5 is a side elevation thereof.

My invention is largely understandable from an inspection of the drawings. However, it should be pointed out that with the frow 5, having its entering edge 50 provided with a plurality of corrugations, that is to say, waved as seen in edge view (see Figure 4), and having a broadened back 51, or like means to permit it to be struck and driven into a block, it is a simple matter to cut from a block, as 2, a plurality of shakes which are of like thickness from end to end, by simply splitting off the successive shakes from one side of the block, without reversing the block end for end. Should the block be reversed end for end, tapered shakes will be split off according to the process disclosed in my former patent, referred to above. Either method may be employed, according to the type of shake desired. However, to illustrate the principle, and as will be noted in Figure 2, after splitting off one shake, the frow is placed at a line of cleavage 20, back from the split edge 21 a distance equal to thickness desired in the next shake, and the frow is driven home along the line of cleavage 20, whereupon the next shake is pried off, and the same steps repeated.

The product, in this particular instance, is the shake shown in Figure 1. The edge 10 of this shake may be taken as the edge which corresponds to the line of cleavage 20 in Figure 2, while the edge 11 corresponds to the line of cleavage at 21 of the block. The face 12 will be seen to have a number of corrugations, or ridges, these continuing throughout the length of the shake, and corresponding to the ridges started by the wavy edged frow along the butt edges 10 and 11, splitting towards the far end of the shake shown in Figure 1. At the far end it will be seen that these ridges 12 are still distinct, though there is some tendency to run out at this end. Western red cedar, and like woods of which shakes are commonly made, is of such fine grain and splits so perfectly that these ridges will extend at least half the length of the shakes, to be distinct and to give the exaggerated effect which is required. Towards the far end they may, perhaps, tend to run out, but the grain of the wood will still preserve these ridges and they will be sufficiently distinct to show up properly, even though the far end be used

as the butt of the shake. As a matter of fact, it is desirable that the effect be not too uniform, and it is an advantage to have part of the shakes with highly exaggerated ridges, and others with less exaggerated ridges, so that the roof may be broken up, and the effect of uniformity relieved.

Such a shake, as shown in Figure 1, may be used without change, but ordinarily, to save stock, and to enable them to be laid as shingles are laid, it is desirable to saw them diagonally along the line 3 and 30, thus producing two tapered shakes from one straight shake. Each such tapered shake will have a sawed surface, and a ridged, or corrugated, surface, which will be placed uppermost when laying the shakes. These ridges too, will form larger drainage channels, and water will tend to collect in these larger channels, rather than follow down the individual small channels, and thus, through the accumulation of drops, will afford better and quicker drainage.

As has been stated such a frow may be employed in the production of tapered shakes, according to the methods of my prior patent, and such shakes will only differ from the tapered shake prepared according to the Runkle process, by having two naturally split and exaggeratedly corrugated faces, either of which may be placed uppermost.

What I claim as my invention is:—

1. A shake having a surface naturally split, and exaggeratedly corrugated to emphasize the natural surface irregularities.

2. A shake having a split surface, and with the natural corrugations thereof exaggerated.

3. A shake having a split surface, and with the natural corrugations exaggerated, the ridges of the several principal corrugations in general defining a plane.

4. A shake tapered from its butt to its tip, the upper face being split to present an exaggeratedly corrugated surface.

5. As an intermediate product, a split shake of substantially like thickness from one end to another, a surface intended for exposure in use having the natural corrugations exaggerated.

6. As an intermediate product, a shake of substantially the same thickness from one end to another, the two faces being naturally split with the natural corrugations exaggerated.

7. A shake sawed diagonally to taper from its butt towards its tip, the face opposite the sawed face being split to exaggerate the natural corrugations, and its under face being plane.

8. A shake tapering from its butt to its tip, the upper face being split to exaggerate the natural corrugations, and its under face being a sawn surface.

Signed at Seattle, King County, Washington this eleventh day of April, 1928.

FRANK L. DIETZ.
